OP D 17,481

DESIGN.

J. L. FOLSON.

CARPET.

No. 17,481.

Patented July 26, 1887.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 17,481, dated July 26, 1887.

Application filed June 15, 1887. Serial No. 241,451. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

The main feature of my design is the figure A, which is repeated on the surface of the car-

pet, as shown. This figure is oval or elliptical in its general contour, with its sides indented, and with a projecting portion at the upper 20 end bent down to one side. The figure is ornamented with small geometric forms arranged in short upwardly and outwardly projecting bands, as clearly shown in the photograph. Any suitable groundwork may be employed. 25

What I claim as new, and desire to secure by Letters Patent, is—

The design for carpets, consisting of the design substantially as shown.

JAS. L. FOLSOM.
